United States Patent Office

Des. 223,055
Patented Mar. 7, 1972

223,055

PHOTOGRAPHIC FILM PROCESSOR

Ralph M. Vigna, Rochester, N.Y., assignor to Eastman
Kodak Company, Rochester, N.Y.

Filed Aug. 27, 1970, Ser. No. 24,733

Term of patent 14 years

Int. Cl. D16—04

U.S. Cl. D61—1

FIG. 1

FIG. 2

FIG. 1 is a front perspective view of a photographic film processor showing my new design;

FIG. 2 is a rear perspective view thereof; the end not shown being plain and unornamented.

I claim:

The ornamental design for a photographic film processor, as shown.
